ACOUSTICAL APPARATUS

Allan W. Fisher, St. Petersburg, Fla.

Application March 3, 1939, Serial No. 259,640

8 Claims. (Cl. 181—31)

This invention relates to acoustical apparatus and more particularly to a loud speaker arrangement in connection with sound reproduction. This application is a continuation in part of co-pending application Serial No. 179,373, filed December 11, 1937.

Acoustical devices for the reproduction of sound and loud speakers in use today fail to present proper tonal effects in that essential resonating features have not been incorporated in their design. Previous to my invention, manufacturers have been reluctant to provide proper resonating means, baffles, sounding board, and flare members because of lack of space in a cabinet of reasonable size with known arrangements of parts.

Most manufacturers of radio sets today are so designing their speakers in relation to the remainder of the apparatus that when sound emanates therefrom a more or less objectionable resonance tones accompany the sound reproduction. These resonance tones are sometimes unpleasant, distasteful, and it may be desirable to vary or eliminate the same.

It is an object of the invention to provide a loud speaker apparatus, having pleasing tonal qualities and resonating features, of compact form.

It is a further object of the invention to provide sound reproducing apparatus including a sounding board having a relatively great freely vibrating area.

It is a still further object of the invention to provide sound reproducing apparatus with an arrangement whereby more or less objectionable resonance tones accompanying the sound reproduction may be controlled by the listener or operator.

Other objects and the nature and advantages of the invention will be apparent from the following description taken in conjunction with the accompanying drawing, wherein:

Fig. 1 is a front elevation of sound reproduction apparatus with parts cut away disclosing portions of a loud speaker arrangement, in accordance with the present invention.

Fig. 2 is a section taken along line 2—2 of Fig. 1 and looking in the direction of the arrows.

Fig. 3 is a fragmentary section taken along line 3—3 of Fig. 2 looking in the direction of the arrows, disclosing the mechanism for controlling the resonance qualities of the apparatus.

Fig. 4 is an enlarged detail sectional view illustrating the valve arrangement on the speaker mounting or auxiliary sounding board and its relation to the main sounding board.

Referring to the drawing, cabinet 10 is arranged to house a sound reproducing apparatus in the upper portion thereof which may take the form of a radio set 11 having a volume control and a switch knob 12, a tuning control knob 13, a tuning dial 14 and resonance control knob 15.

In the lower portion of the cabinet 10 an inclined main sounding board 16, which may be fabricated of wood or other suitable material, is supported along its peripheral margins P in 10 a manner to permit free vibration throughout its width and length. Similarly supported along its peripheral margins P' a speaker mounting and auxiliary board A are arranged in spaced parallel relation to the main sounding board 16. This 15 auxiliary board A may be fabricated of one-quarter inch fiber board or other suitable material of corresponding dimension. Though the parts may be manufactured in any size, when the main sounding board 16 is approximately twenty-four inches square a spacing of from approximately one-half to one inch, preferably three-quarters inch, is utilized between the main sounding board 16 and the auxiliary board A. A flare member 18, which may take the form of a hollow 20 frustrated cone, is secured to the rear portion of the auxiliary board A and the peripheral margin M of the outlet of the speaker 17 which may be of a conventional type is also secured and supported by the said auxiliary board. 25

The main sounding board 16 has arranged thereon and therethrough a desired number of resonating tubes 19 mounted in rubber or other resilient bands or sleeves R at their bases. In Fig. 1 a plurality of resonating tubes 19 are illustrated, which tubes attribute to the device proper pleasing tonal effects. This group of tubes 19 cover a diatonic range of two octaves. The tubes 19 are arranged on the main sounding board 16 in a manner such that their axes are 35 substantially perpendicular to the sounding board and in alignment with the loud speaker 17, the axis of which is also substantially perpendicular to the main sounding board. The tubes 19 are further arranged in a manner such that their 40 front faces 20 lie in a plane substantially parallel to the front of the cabinet and intersect said plane to form ellipses, as shown in Fig. 1. In effecting this arrangement the shorter tubes are placed in the bottom of the main sounding board 45 16 which is inclined in a manner whereby its bottom portion is relatively close to the front of the cabinet, its top portion is relatively remote from the front of the cabinet and the succeeding longer tubes are arranged higher up on the main 50 55

sounding board 16, as illustrated in the drawing.

In addition to the tubes 19 that transmit the tone from the front of the speaker, another set of tubes 21 may be arranged in circular form about the tubes 19 and through the main sounding board 16 in communication with the space between flare member 18 and housing 22 which envelops speaker 17 but is arranged in spaced relation thereto and secured to the rear side of auxiliary board A in a manner to cooperate with the rear portions of the tubes 21 whereby they may carry sound that originates from the rear of the speaker which involves more or less objectionable resonance tones. The resonating tubes 19 cooperate with the set of tubes 21 to boost or convert the tonal range to one that is chromatic having half tones throughout. Thus, it will be seen that the tubes 21 act in a sense as "booster" tubes for the sound that ordinarily emanates from the rear portion of the speaker, when projected forward and mixed with the main speaker output, loses its objectionable qualities and becomes a valuable asset. The housing 22 may or may not be fabricated of sound deadening material, such as felt paper, for example.

In practice I have found that the sound that emanates from the speaker is weaker at or near its circumference and to compensate for this weakness tubes 21 have been provided to bring additional volume from the rear of the speaker which more or less equalizes the sound emanating from substantially the entire area of the sounding board. Should this added sound be too great for the room or listener, I may provide a control, comprising knob 15 cooperatively associated with shaft 23 in a manner whereby through worm and gear mechanism 24, the shaft 25 may rotate pulley 26 winding thereon wire 27 which is attached to rotate at annular disc 28, at ear 28, causing said annular disc to rotate in the direction of the arrow as shown in Fig. 3. Tending to pull rotating annular disc back to its original position is spring 30 fixed to a portion of the cabinet by hook 31 at one end and at its other end fastened to wire 32 which engages ear 33 of the rotating disc 28. Guide means 34 secured to the front side of auxiliary board A may be provided in cooperative relation to rotating disc 28 whereby circular openings 35, arranged in said annular disc to correspond with the rear openings in tubes 21, may transmit all, part, or substantially prevent the transmission of sound from the rear of the speaker through tubes 21 to the listener, depending upon the position of the annular disc 28 which in turn is controlled by the knob 15. The annular disc 28 may be fabricated of one-quarter inch fiber board, or any other suitable material and in corresponding dimension.

On the front of the sounding board encasing the resonating tubes 19 and tubes 21, a casing 36 may be provided with a substantially circular cross section at its base 37, and an inwardly curved portion at its front end 38. The casing 36 may be fabricated of a sound deadening material such as paper or the like. With this arrangement sound emanating from the resonating tubes will be concentrated and prevented from spreading over a wide area thereby giving warmth to the sound reproduction which is noticeably pleasant. The casing 36 is similar in design to the shape formed by a singer's lips to concentrate the sound emanating from his mouth and which gives a mellow effect thereto.

The tubes 21 arranged about the resonating tubes 19, may be considered as semi-tones from a

voicing angle, and in combination with the tubes 19 form a chromatic scale of tones, one-half tones from bottom to top, which adapt themselves to those emanating from speaker 17, so that regardless of the position of the disc 28 or the use of same to moderate the volume of tone which originates from the rear of the speaker, all sound, light or strong, goes through tubes 21. The use of speaker mounting and sounding board in conjunction with the tubes 21 prevents the elimination of tones emanating from the peripheral regions of the speaker which not only have musical value but make more uniform the flow of sound to the listener for they act to boost the power at points remote from the center of the apparatus, which points most need boosting as the speaker like a spot light is more powerful at its center, points remote from the center shading off. Whether the rotating disc 28 is in such position as to effect closing of the openings 35 or not, the sound travels the entire chromatic scale covering better than two octaves and sound above or below adapts itself to these base or fundamental tones.

With the arrangement described, sound may be reproduced in a pleasing and effective manner with the absence of harsh vibrant effects, with a control of the more or less objectionable resonance tones emanating from the rear of the speaker and in a greater volume without distortion. Frequently, a listener to, or operator of, a radio set, as manufactured today, will be unable to satisfactorily hear the tones of the various instruments of the original composition unless the volume control is turned up to a point where it is no longer pleasing, because of the accompanying excess noise or volume. With my invention, however, it is possible to reduce the size of the speaker proper and still receive the desired tonal effects which makes it feasible to produce a console at lower cost without affecting the quality of reproduction.

It will be obvious to those skilled in the art that various changes may be made in this device without departing from the spirit of the invention and therefore the invention is not limited to what is shown in the drawing and described in the specification but only as indicated by the appended claims.

I claim:

1. An acoustical device comprising a main sounding board, a plurality of resonating tubes mounted on and through said main sounding board, said main sounding board being supported at its periphery whereby free vibration throughout the major surface of said main sounding board may be effected, an auxiliary board having a first opening therein mounted in spaced relation to said main sounding board, said auxiliary board being supported at its periphery whereby free vibration throughout its major area may be effected, sound producing means adjacent said opening in said auxiliary board, said auxiliary board having a second opening located in spaced relation to said first opening, a housing cooperating with said auxiliary board to envelop said sound producing means and said first and second openings, a resonating tube mounted on said main sounding board and communicating with said second opening.

2. The structure recited in claim 1, and means for varying the communication between said resonating tube and the opening in the auxiliary board spaced from said sound producing means.

3. An acoustical device of the class described

comprising an inclined main sounding board with its upper part tilted rearwardly and its lower part tilted forwardly, an auxiliary board having an opening therein and arranged in spaced relation to said main sounding board, said main sounding board and said auxiliary board being supported at their respective peripheries whereby free vibration throughout their major areas may be effected, sound producing means arranged 5 on the rear side of said auxiliary board with the front portion of the sound producing means adjacent said opening therein, resonating tubes arranged on the front side of said main sounding board, said resonating tubes being of varying 10 lengths and having their axes generally normal to the main sounding board, the longer size tubes being arranged above the shorter size tubes, whereby the front edges thereof lie in a substantially vertical plane and whereby a minimum 15 20 of space is occupied, said auxiliary board having a second opening therein communicating the back of said sound producing means with a resonating tube arranged on the front side of said main sounding board.

25 4. The structure recited in claim 3, the bases of said tubes being insulated from said main sounding board by resilient bands.

5. The structure recited in claim 3, and means for varying the area of said second opening to 30 vary the communication between the rear side of said sound producing means and at least one of said resonating tubes.

6. An acoustical device comprising a main sounding board having first and second openings therein, an auxiliary board supported in spaced relation thereto and having a first and second opening therein, said boards being supported at 5 their peripheries to permit free vibration throughout their planular areas, sound producing means having its front side adjacent the first opening in said auxiliary board, the first opening in said main sounding board communicating with the 10 first opening in said auxiliary board, a housing in spaced relation to said sound producing means and cooperating with said auxiliary board to envelop said sound producing means whereby the second opening in said main sounding board 15 and the second opening in said auxiliary board will communicate with the space between the housing and the rear side of said sound producing means.

7. The structure recited in claim 6, and valve 20 means for varying the communication between the second opening in said main sounding board and the space between the housing and the rear side of said sound producing means.

8. The structure recited in claim 6, and valve 25 means for varying the communication between the second opening in said main sounding board and the space between the housing and the rear side of said sound producing means, said valve means being manually adjustable. 30
